UNITED STATES PATENT OFFICE.

RHODOLPH H. FRANKLIN, OF BROOKLYN, NEW YORK, ASSIGNOR TO
CHARLES C. CUMMINGS, OF SAME PLACE.

WATCH-MAKER'S TWEEZERS.

SPECIFICATION forming part of Letters Patent No. 437,647, dated September 30, 1890.

Application filed March 27, 1889. Serial No. 305,022. (No model.)

To all whom it may concern:

Be it known that I, RHODOLPH H. FRANKLIN, a citizen of the United States, residing at Brooklyn, in the county of Kings and State 5 of New York, have invented certain new and useful Improvements in Tweezers; and I do hereby declare the following to be a full, clear, and exact description of the invention, such as will enable others skilled in the art to which 10 it appertains to make and use the same.

My invention consists of the improved construction and arrangement of tweezers hereinafter described and claimed, which consist, generally, of a pair of jaws that spring open 15 on being forced out of one end of the inclosing case by pressure on a push-stud at the other end and close on and grip objects to be handled by them by the action of a retracting spring within the case, all as follows, reference being made to the accompanying drawings, in which—

Figure 1 is a side elevation of my improved tweezers with plain jaws for general purposes. Fig. 2 is a sectional elevation of the same in 25 a plane at right angles to the view of Fig. 1, with dotted lines showing the jaws thrust out and opened. Figs. 3 and 4 are side views showing the jaws specially adapted for handling jewels.

30 *a* represents the tubular case; *b*, the jaws; *c*, the tapered spring-shanks of the jaws, which open them as the said tapered portions shift outward along the mouth of the tube, said jaws being closed by the case when shifted 35 the other way. *d* is the push-stud attached to the upper end of the shanks of the jaws, joined and secured together in one staff *j* a suitable distance above the spring-shanks; and *f* is the coiled spring in the upper part 40 of the case, resting on the shoulder *g* and bearing on the lower end of the push-stud with the force required to thrust the jaws back into the case to close and grip the objects to be handled by shifting the inclines *c* 45 inward of the mouth of the tube.

As thus far described, the device is substantially the same as the well-known Birch universal watch-key, which is the subject of several patents, and I make no claim herein 50 to any of these features, my invention being in the peculiarities of construction described

farther on, which I have worked out to enable the principle of the watch-key to be utilized for tweezers.

In a watch-key of the kind in question the 55 jaws are grooved in the gripping-faces to the dimensions of the winding-posts of the smallest size, and so that they require to open but slightly or not at all for such posts, and the range of opening for larger posts is only the 60 difference in the size of posts of different watches, which at most is very little. Another 65 feature of the key is that the jaws surround and inclose the posts in their grip.

The slight range of opening of the jaws, 70 together with the wide dimensions necessary for inclosing the posts of the watch, enable 75 practicable keys to be produced with a small case, which is unobjectionable as to size, the width of the material furnishing the strength 80 for the grip with less thickness than would otherwise be required, and the size of the tube being smaller in proportion as the range of opening is short; but the jaws occupy nearly 85 the whole area of the bore of the tube in order to have the required width for inclosing the post, and in order to be able to open they have to taper in the plane of their opening as well as at the back, which, although not materially objectionable in the short-range 90 jaws of watch-keys, both in the opening and the lengthwise movement, would be fatal in the case of jaws necessarily having the much longer range, which tweezers-jaws must have in both ways, for they would not close accurately on each other and would fail to hold objects such as the instrument is designed to 95 handle, owing to the slack side fit of the jaws in the tube.

While it is true that tweezers might be 100 made on the plan of the watch-key that would have the proper range of opening for tweezers, such tweezers would be unsatisfactory, because the case would be too large and clumsy for practical use. I have therefore contrived to produce tweezers on the plan of the watch-key, having the necessary range of opening for such instruments and in practicable size of the case by making the jaws much thinner in the plane of the division between them 105 than the watch-key jaws must be for their purposes and wider in the other direction.

than the case, and also slotting the case some distance back from the end, as shown at *h*, for laterally guiding and controlling the jaws sliding in said slot, and which when closed 5 project through said slots flush with or a little beyond the exterior surface of the tube, as at *k*, and also making the inclines *i* within the case from the outer angles at the ends of slots *h* backward, together with the coacting 10 inclines of shanks *c* of the jaws, beginning at the outer edges of the jaws, so that the longest range of inclines attainable in the case is secured, and thus the jaws will open as wide as desired in a case much smaller than 15 it would have to be in the key arrangement, and the jaws have much greater breadth and strength in the direction in which the grip is effected, which is important because of the much longer jaws required in the tweezers 20 than in the key.

The jaws may be variously formed for various special purposes, as the curved and pronged form represented in Figs. 2 and 3, adapted for handling diamonds.

25 The push-stud *d* is screwed onto the upper end of the jaw-staff, and is fitted to screw more or less thereon to alter the tension of the spring *f*, according as the jaws are desired to grip with more or less force. The 30 push-stud has a stop socket or groove *t* made in the side, and a spring-stop *u* is attached to the upper end of the case in such suitable relation to the socket or groove that when said push-stud is pressed into the case to the limit 35 of its range the stop will drop into the socket or groove and hold the jaws in the extended position when required. The groove is preferred to the socket, said groove being made only partly around the push-stud with the 40 ends gradually vanishing in the surface, so that the push-stud can be quickly released

from the stop by turning the push-stud so as to shift the groove away from the stop and leave it on the plain surface of the push-stud; but the socket may be used, the stop being in 45 such case suitably contrived for being forced out of the socket by the finger-nail or other approved means. There is a shoulder *l* to serve in connection with collar *m* on the staff *j* to limit the extent to which the jaws will be 50 thrust out.

The shoulders *g* and *l* are in this example produced by spinning the grooves *e* in the exterior of the tube, but they may be provided in any other approved way.

55

I claim as my invention—

1. In tweezers consisting, essentially, of the tubular case, inclosed jaws, push-stud, and retracting spring arranged for the opening and closing of the jaws by shifting them outward and inward of the case, said case having the slots *h* for the jaws cut through the shell and extended upward along the same a suitable distance from the end, and the jaws fitted in said slots and at the back extending 60 through the slots flush with the outer surface of the shell or thereabout when closed, said jaws having the usual taper spring-shanks, push-piece, and retracting spring, substantially as described.

2. The combination of the spring-stop on the case, with the push-stud, jaws, and retracting spring, said stud having a short groove extending partly around it for the stop and vanishing at the ends in the surface of the 75 push-stud, substantially as described.

In testimony whereof I affix my signature in presence of two witnesses.

RIODOLPHI II. FRANKLIN.
